UNITED STATES PATENT OFFICE.

EDWARD E. PINKERTON, OF CHICAGO, ILLINOIS.

FOLDING BOX.

1,383,148.

Specification of Letters Patent. Patented June 28, 1921.

Application filed August 8, 1917. Serial No. 185,063.

To all whom it may concern:

Be it known that I, EDWARD E. PINKERTON, a citizen of the United States, and a resident of the city of Chicago, county of 5 Cook, and State of Illinois, have invented certain new and useful Improvements in Folding Boxes, of which the following is a specification.

My invention relates to improvements in 10 folding boxes, and has for its object the provision of an improved construction of this character, which is simple and efficient in use, and especially adapted for use as a laundry box.

15 The invention consists in the combinations and arrangements of parts hereinafter described and claimed.

The invention will be best understood by reference to the accompanying drawings 20 forming a part of this specification, and in which—

Figure 1 is a plan view of the box spread out in flat form,

Fig. 2, a perspective view of the box made 25 up and closed,

Fig. 3, a longitudinal section of the box, and

Fig. 4, an enlarged transverse section of 30 the box.

The preferred form of construction as 35 illustrated in the drawings comprises an ordinary folding box made up of a bottom 5, side walls 6 and end walls 7, provided with tongues 8 adapted to enter slits 9 in the side walls and thus form the ordinary 40 form of folding box body. Top members 10 and 11 are formed at the upper edges of the side members 6 and of a width adapted to cover the top of the box, the top member 45 11 being provided with slits 12 at its free edge adapted to receive the edges of the top member 10 as indicated in Fig. 2. The ends of top member 10 are provided with tongues 13 adapted to enter slits 14 provided in the

45 end walls 7, to hold the cover in closed relation. Flaps 15 are provided on the ends

of cover member 11 and are adapted to be inserted within the box, resting on the bottom thereof, and serve to reinforce and stiffen the top member 11.

50 While I have illustrated and described the preferred form of construction for carrying my invention into effect, this is capable of variation and modification without departing from the spirit of the invention. I, 55 therefore, do not wish to be limited to the precise details of construction set forth, but desire to avail myself of such variations and modifications as come within the scope of the appended claim.

60 Having described my invention what I claim as new and desire to secure by Letters Patent is:

A folding box comprising a bottom; foldable side and end walls therefor; top members at the upper edges of said side walls, each of said top members being of a size to extend slightly over half way across the top of the box and overlap at their free edges, there being slits opening at the free edge 70 of the innermost of said top members, adapted to receive the free edge of the uppermost of said top members; interlocking tongues at the edges of said end walls, there being slits in said side walls adapted 75 to receive said tongues; tongues at the opposite ends of the outermost of said top members, there being slits in the end walls adapted to receive said tongues; flaps at the ends of the innermost of said top members, adapted and arranged to be inserted within the 80 box and contact with the bottom thereof to support said top members, substantially as described.

In testimony whereof I have signed my 85 name to this specification in the presence of two subscribing witnesses.

EDWARD E. PINKERTON.

Witnesses:

JOSHUA R. H. POTTS,
JANET E. FARRELL.
